**PORTABLE TELEVISION RECEIVER OR
SIMILAR ARTICLE**

David Chapman and Marlan Polhemus, Chicago, Ill., as
signors to Radio Corporation of America, a corpora-
tion of Delaware

Filed May 20, 1966, Ser. No. 2,368

Term of patent 14 years

(Cl. D56—4)

Fig. 3.

Fig. 4.

*Fig. 5.*FIGURE 1 is a front perspective view of a portable television receiver or similar article, showing our new design with the hinged control and loudspeaker panel in a tilt-up operating position;

FIGURE 2 is a side elevational view of television receiver shown in FIGURE 1, the opposite side being substantially a mirror image thereof;

FIGURE 3 is a front elevational view of the television receiver with its control panel in a tilt-down closed position;

FIGURE 4 is a top plan view of FIGURE 3; and

FIGURE 5 is a rear elevational view of FIGURE 3.

We claim:

The ornamental design for a portable television receiver or similar article, substantially as shown and described.
